Primary Examiner — Paula Allen Greene(74) *Attorney, Agent, or Firm* — Nath, Goldberg & Meyer; Jerald L. Meyer(57) **CLAIM**

The ornamental design for pair of earphones, as shown and described.

DESCRIPTION

FIG. 1 is a right side perspective view of pair of earphones showing my new design;

FIG. 2 is a left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines immediately adjacent the shaded areas represent the bounds of the claimed design while all other broken lines are directed to environment and are for illustrative purposes only; the broken lines form no part of the claimed design.

1 Claim, 8 Drawing Sheets(56)
